TENSION CONTROLLING MEANS FOR TRAVELING OFFSET WEBS

Application filed January 2, 1930. Serial No. 417,897.

In multicolor web perfecting presses where a traveling offset web is led around the impression cylinder of the second printing unit under the printed web, it has been difficult to obtain clean and sharp printing.

I have discovered that if the tension on the offset web necessary to the proper rewinding thereof be eliminated where the offset web is in contact with the impression cylinder of the second printing unit thus permitting the offset and printed webs to travel together around the impression cylinder, clean and sharp printing will be obtained.

To accomplish this I provide the following means located between the second printing unit and the offset web rewinding mechanism:—

First, a guide roller for taking the offset web away from the impression cylinder under the same tension as the printed web; second, a compensating device for the offset web, and third, an offset web tension controlling mechanism through which the offset web is passed and given sufficient tension to produce a perfect roll in the rewinding mechanism.

In practice, the travel of the printed web per cylinder revolution varies with the different forms used on the form cylinders, thus making it next to impossible to properly proportion the guide rollers of the offset web tension controlling mechanism so that they will travel with the offset web under all conditions. It is to prevent this variation from disturbing the offset web that I interpose a compensating device between the positively driven roller for taking the offset web away from the impression cylinder and the offset web tension controlling mechanism.

A practical embodiment of my invention is represented in the accompanying drawing, in which the form and impression cylinders of the second printing unit are denoted by 1, 2, 3, 4 and 5. The traveling printed web is denoted by 6 and the traveling offset web by 7, which offset web is shown as leading from the supply roll 8 around the impression cylinder 5 to the take-up roll 9 of the offset web rewinding mechanism. This rewinding mechanism in the present instance

is shown as a compressing pair of rollers 10 and 11 driven from the gear 12 on the shaft of the impression cylinder 5 through the train of gears 13, 14, 15, 16, 17, 18, 19, 20 and 21.

The offset web tension controlling mechanism is shown herein as comprising a plurality of guide rollers 22, 23, 24, around which the offset web is passed on its way from the second printing unit to the rewinding mechanism. These guide rollers 22, 23, 24 are driven from the gear 17 through the gears 25, 26, 27 at the desired speed so that the tension necessary to the correct rewinding of the offset web is taken up by the guide rollers and is not transmitted to the second printing unit.

The printed web and the offset web are taken off from the impression cylinder 5 at the same tension by providing the printed web guide roller 28 and the offset web guide roller 30. The guide roller 28 is driven from the gear 15 through the gear 29 and the guide roller 30 is driven from the gear 15 through the gears 31, 32 and 33.

The offset web compensating device is shown as comprising a gravity operated take-up roller 34, mounted in a swinging support 35 and resting upon the offset web between the guide roller 30 and the roller 22 of the offset web tension controlling mechanism.

If the travel of the rollers 22, 23, 24 of the offset web tension controlling mechanism is slow the offset web is threaded with a slight slack with the compensating roller occupying the position shown in long broken lines at *a*, thereby allowing the roller to maintain its pressure on the web as the slack increases. If the travel of the said rollers 22, 23, 24 of the offset web tension controlling mechanism is fast the offset web is threaded with a considerable slack with the compensating roller occupying the position shown in short broken lines at *b*, thereby allowing the roller to maintain its pressure on the web as the slack decreases.

The above arrangement causes the offset and printed webs to travel together around the impression cylinder and thereby ensures

clean and sharp printing on the printed web.

It is evident that various changes may be resorted to in the construction, form and arrangement of the several parts without departing from the spirit and scope of my invention; hence, I do not intend to be limited to the particular embodiment herein shown and described, but

What I claim is:—

- 10 1. In a multicolor web perfecting printing press, a printing unit, a traveling offset web, an offset web rewinding mechanism, a web tension controlling mechanism therefor, and a web compensating device located between the printing unit and said web tension controlling mechanism.
- 15 2. In a multicolor web perfecting printing press, a printing unit, a traveling offset web, an offset web rewinding mechanism, means for taking the offset web away from the printing unit under the same tension as the web printed thereby, an offset web tension controlling mechanism for the rewinding mechanism, and a web compensating device located between the printing unit and the offset web tension controlling mechanism.
- 20 3. In a multicolor web perfecting printing press, a printing unit, a traveling offset web, an offset web rewinding mechanism, web tension controlling rollers around which the offset web is passed on its way to the rewinding mechanism and a web compensating device comprising a take-up roller pressing against said offset web between the printing unit and the web tension controlling mechanism.
- 25 4. In a multicolor web perfecting printing press, a printing unit, a traveling offset web, an offset web rewinding mechanism, a roller for taking the offset web away from the printing unit under the same tension as the web printed thereby, web tension controlling rollers around which the offset web passes to the rewinding mechanism, and an offset web compensating roller located between said printing unit and said tension controlling rollers.

In testimony, that I claim the foregoing as my invention, I have signed my name this 50 30th day of December, 1929.

HOWARD M. BARBER.
